(57) **CLAIM**

The ornamental design for a flat cord clip, as shown and described.

DESCRIPTION

FIG. 1 is a top isometric view of a flat cord clip according to an embodiment disclosed herein;

FIG. 2 is a bottom isometric view of a flat cord clip according to an embodiment disclosed herein;

FIG. 3 is a top plan view of a flat cord clip according to an embodiment disclosed herein;

FIG. 4 is a bottom plan view of a flat cord clip according to an embodiment disclosed herein;

FIG. 5 is a front elevation view of a flat cord clip according to an embodiment disclosed herein;

FIG. 6 is a side elevation view of a flat cord clip according to an embodiment disclosed herein;

FIG. 7 is a front cross-sectional view of a flat cord clip, taken along line 7-7 of FIG. 3, according to an embodiment disclosed herein;

FIG. 8 is a side cross-sectional view of a flat cord clip, taken along line 8-8 of FIG. 3, according to an embodiment disclosed herein;

FIG. 9 is a side cross-sectional view of a flat cord clip, taken along line 9-9 of FIG. 3, according to an embodiment disclosed herein;

FIG. 10 is a top cross-sectional view of a flat cord clip, taken along line 10-10 of FIG. 5, according to an embodiment disclosed herein;

FIG. 11 is a bottom cross-sectional view of a flat cord clip, taken along line 11-11 of FIG. 5, according to an embodiment disclosed herein; and,

FIG. 12 is an environmental view of a flat cord clip according to an embodiment disclosed herein.

The broken lines are directed to the unclaimed cord and are presented to illustrate an environmental structure in which the flat cord clip can be positioned. The broken lines form no part of the design to be patented.
